DESIGN FOR A MANTEL CLOCK

Harry Levitan, Chicago, Ill.

Application January 24, 1946, Serial No. 125,936

Term of patent 7 years

(Cl. D42—7)

To all whom it may concern:

Be it known that I, Harry Levitan, a citizen of the United States of America, residing at Chicago, in the county of Cook and State of Illinois, have invented a new, original, and ornamental Design for Mantel Clocks, of which the following is a specification, reference being had to the accompanying drawing, forming a part thereof.

Fig. 1 is a front perspective view of a mantel clock, showing my new design.

Fig. 2 is a perspective rear view.

I claim:

The ornamental design for a mantel clock, substantially as shown.

HARRY LEVITAN.
